[57] **CLAIM**

The ornamental design for portable navigation light system for barges, as shown and described.

DESCRIPTION

FIG. 1 is a perspective view of a portable navigation light for barges showing my new design, this being the starboard side light; while

FIG. 2 is a top view thereof;

FIG. 3 is a front view thereof; and

FIG. 4 is a right side view thereof.

FIG. 5 is a perspective view of a second embodiment of my design, this being the port side light; while

FIG. 6 is a top view thereof;

FIG. 7 is a front view thereof; and

FIG. 8 is a left side view thereof.

FIG. 9 is a perspective view of a third embodiment of my new design, this being the special flashing light; while

FIG. 10 is a top view thereof;

FIG. 11 is a front view thereof; and

FIG. 12 is a right side view thereof.

FIG. 13 is a perspective view of a fourth embodiment of my design, this being the sternlight; while

FIG. 14 is a top view thereof;

FIG. 15 is a front view thereof; and

FIG. 16 is a right side view thereof.

The rear and bottom surfaces of all embodiments, the left side surfaces of the first, third and fourth embodiments, and the right side surface of the second embodiment are flat and unornamented.

FIG. 2FIG. 3FIG. 4FIG. 1FIG. 5FIG. 6FIG. 8FIG. 7FIG. 10FIG. 11FIG. 12FIG. 9FIG. 14FIG. 15FIG. 16FIG. 13
